Mark Cangen
BY Hauff Marland
ATTORNEYS

UNITED STATES PATENT OFFICE.

MARK CANGEN, OF BROOKLYN, NEW YORK.

HEEL FASTENER.

Application filed August 18, 1924. Serial No. 732,715.

To all whom it may concern:

Be it known that I, MARK CANGEN, a citizen of the United States, residing at Brooklyn, in the county of Kings and State of New York, have invented new and useful Improvements in Heel Fasteners, of which the following is a specification.

The invention relates to a device and method of fastening wood heels to shoes and it provides a pronged plate secured to the top of the heel, the prongs being clinched to the sole of the shoe thus rigidly holding the heel to the sole obviating the employment of nails.

15 The invention is especially designed to provide a hook projecting from one end of the plate for centering the heel on the sole and then clinching the hook to the sole by forcing the heel against a last arranged in the shoe.

The present invention provides a simplified method of immovably fastening the heel to the shoe by partly slitting the sole, then spreading a layer of glue over the heel and sole, inserting the hook into the slit and forcing the heel downward onto the last to clinch the prongs and hook to the sole.

Heretofore, the glued heel was held in place on the sole by a removable clamp or a screw passed through the last, the screw was removed after the heel was shaped and the glue set, and finally the heel was nailed to the sole from the inside of the shoe.

The invention resides more particularly in the novel combinations hereinafter described and claimed, reference being made to the accompanying drawing in which:—

Fig. 1 represents a perspective view of a heel embodying this invention.

40 Fig. 2 is a vertical section showing the heel positioned on the sole.

Fig. 3 is a transverse section taken along the line 3-3 of Fig. 2 showing the heel fastened to the sole.

45 In the drawing the numeral 5 designates a heel which is made of wood or suitable material and can be of any well-known shape. On the upper portion of the heel is fastened by means of screws or nails 6 a plate 7 having a turned end to form a hook 8 and a pair of prongs 9 formed

by bending the plate upwardly at the other end. The plate is countersunk into the wood so as to give an even or flush surface on top. Lateral spurs 10 forming an integral part of the hook and a notch 11 on the lower part of each prong prevents the devices from being pulled out of the material.

55 The method of fastening the heel to the shoe consists in partly slitting a sole 12 at 14, coating the top of the heel and lower part of the sole with glue, positioning the heel over the sole so that the hook engages the slit, and then forcing the prongs into the sole by hammering down the heel on a last 15 with a metal plate 16 fixed to its bottom. The last is arranged inside of the shoe and by its pressure it forces the hook downward as indicated in dotted lines in Fig. 2 to clinch the material. At the same 60 time the forward prongs will be bent over at their tops laterally as shown in Fig. 3, thus rigidly fastening the heel to the shoe.

65 It will be readily understood, that in this method the glue can be omitted but it is preferred to use glue or cement to fill or waterproof the joints. It has been found by practice that the heel is firmly anchored to the sole after the prongs and the hook are clinched to the leather.

70 I claim:—

1. A heel fastener having a hook for engagement with a slitted sole, and a prong made to clinch the sole.

2. A heel fastener comprising a plate having a hook for engagement with a slitted sole, and a prong projecting from the plate made to clinch the sole.

3. A heel fastener comprising a plate having a turned end to form a hook for engagement with a slitted sole, and a prong projecting from the other end made to clinch the sole.

4. A heel fastener comprising a plate having a turned end to form a hook for engagement with a slitted sole, and a prong formed by bending the other end of the plate upwardly made to clinch the sole.

5. A heel fastener comprising a plate having a turned end to form a hook for engagement with a slitted sole, a pair of prongs formed by bending the other end of

the plate upwardly made to clinch the sole, and means for fastening the plate to a heel.

6. The method of fastening a heel to a shoe sole, which consists in providing the heel with a hook and a prong, slitting the sole to engage the hook, forcing the prong into the sole, and clinching the hook and prong to the sole.

7. The method of fastening a heel to a

shoe sole, which consists in providing the heel with a plate having a hook at one end and a pair of prongs at the other end, slitting the sole to engage the hook, forcing the prongs into the sole, and clinching the hook and prongs to the sole.

In testimony whereof I have hereunto set my hand.

MARK CANGEN.
